PORTABLE OUTDOOR FIREPLACE

Charles W. Smith, Bellevue, Wash.

Application March 13, 1958, Serial No. 50,019

Term of patent 14 years

(Cl. D81—10)

Fig. 1 is a perspective view of my portable outdoor fireplace;

Fig. 2 is a front elevational view of the fireplace;

Fig. 3 is a side elevational view of the fireplace;

Fig. 4 is a rear elevational view of the fireplace; and

Fig. 5 is a top plan view of the fireplace.

I claim:

The ornamental design for a portable outdoor fireplace, as shown.
